UNITED STATES PATENT OFFICE.

ALBERT B. PULLMAN, OF CHICAGO, ILLINOIS.

URINAL.

SPECIFICATION forming part of Letters Patent No. 293,275, dated February 12, 1884.

Application filed March 2, 1883. (No model.)

To all whom it may concern:

Be it known that I, ALBERT B. PULLMAN, a citizen of the United States, residing at Chicago, in the county of Cook and State of Illinois, have invented certain new and useful Improvements in Urinals; and I hereby declare the following to be a full, clear, and exact description of the same.

My invention relates to urinals for railway-cars, and for all other places in which they are employed.

A fault of all urinals as now constructed is that the basin is placed too high, rendering a drip-pan upon the floor necessary to prevent fouling of the apartment. This fault is especially noticeable in railway-cars, where the unsteady motion greatly increases the difficulty of using, though it exists in a greater or less degree under all circumstances. Moreover, the urine is ordinarily conducted away from the basin by a slender metallic pipe leading out through the floor, which pipe soon becomes foul, and cannot be cleaned thoroughly without great trouble.

The objects of my invention are to provide a urinal in which the basin shall be so near the floor as to render a drip-pan beneath unnecessary, and also to secure the whole device in position in such a way that for purposes of cleansing it may readily be detached from the wall and carried out of its apartment, and after cleansing be readily replaced in position. It may be detachably connected to the wall by any one of many well-known devices; but I have contrived a device especially suitable to the purpose, which will be hereinafter described.

I accomplish the above objects, first, by providing the basin with a back either synclinal or concave, (or of any other form that will produce a vertical channel,) extending upward to the required height, and providing it underneath with a wide convergent extension reaching to the floor, and connecting there with the waste-pipe; and, secondly, by detachably securing the device so constructed in position. The length of the convergent extension should be such as to bring the basin near the floor. The effect of this construction is not only to make the urinal more convenient and agreeable to use, and to obviate the necessity of a drip-pan beneath, since the basin itself performs the

function of a drip-pan in addition to its ordinary functions, but it also protects the feet and garments of the user.

The expression "detachably secured" is to be understood in a limited sense—namely, in contradistinction to the permanent fastening which is afforded by screws and the like.

My invention consists in the general features above outlined, and, furthermore, in certain details of construction and combinations of parts, all as hereinafter more fully set forth.

In the accompanying drawings, Figure 1 is a front elevation of a urinal provided with all my improvements; Fig. 2, a plan view of the same; Fig. 3, an elevation, partly in section, of the lower part of the urinal, showing the interior construction at the base; Fig. 4, an enlarged vertical section taken on the line 4-4 of Fig. 1, showing the interior construction of a suitable device for detachably connecting the urinal to the wall; Fig. 5, a plan view of the attaching device; Fig. 6, a plan view of the top of the urinal detached; Fig. 7, a plan view of the cover for the outlet at the bottom of the urinal, and Fig. 8 a cross-section of the same on the line 8-8 of Fig. 7.

A is the basin of the urinal, which is provided underneath with the wide convergent extension B, reaching to the floor, and which is extended into the high channeled back C above. The length of the extension B should preferably be such as to raise the basin a foot, or about that distance, above the floor D, while the back should be sufficiently high to extend from two and one-half to three feet above the floor. The basin, back, and downward extension are formed in one piece, ordinarily from porcelain. The lower end of the extension B fits into the upper end of a waste-pipe, E, extending down through the floor, and may be provided with a rubber packing, v, below the external shoulder, u. For railway-cars, the waste-pipe E may be made as wide in proportion as it is represented in the drawings, and flaring downward, as shown. Of course, the larger the waste-pipe the more readily it can be kept clean. On the inside of the extension B is a shoulder, t, upon which the removable cover F is supported. This cover comprises a concave body, s, having an outlet-orifice, r, over which is arched a plate, q, provided with a handle, p. Any fluid entering the basin finds

its way down through the extension B, and, by way of the passage o, at the sides of the plate q, through the orifice r into the waste-pipe.

The device before referred to for detachably connecting the urinal to the wall is represented in Figs. 4, 5, and 6, and is as follows: G is a top for the urinal, provided with a socket, n. H is a casing, through which passes a bolt, I, surrounded by a helical spring, K, within the casing, and terminating in a head, m, above the same. The spring is confined between the top of the casing and a pin, l, passing through bolt. The casing is screwed to the wall above the place for the urinal at such a height that the lower end of the bolt will be somewhat lower when at its lowest point than the top of the socket n. To insert the urinal, the lower end, k, of the bolt is inserted in the socket n, and the bolt forced upward, in opposition to the spring, sufficiently to permit the lower end of the pipe B to be inserted in the top of the waste-pipe E. The force of the spring then tends to hold the urinal firmly in place. To detach it, the urinal is lifted upward in opposition to the spring until the lower end is free from the waste-pipe, after which it is readily released from the bolt at the top.

The drawings represent a urinal designed for a corner. If, however, it is intended for any other position, such changes only will be required in matters of form and construction as will readily suggest themselves to the mind of any person skilled in the manufacture of such devices, and therefore they need not be set forth here. Some of these, relating to the attaching devices and to the different forms which may be given to the channeled back, have already been suggested.

The removable cover F affords facilities for cleansing and for removing any foreign substances which may find their way into the urinal and tend to clog the outlet. If preferred, however, a permanent bottom may be provided having outlet-openings in the usual form.

What I claim as new, and desire to secure by Letters Patent, is—

1. A urinal comprising the basin A, provided with a downward extension, B, to connect with the waste-pipe at the floor, and with the high channeled back C, substantially as described, and for the purpose set forth.

2. In a urinal, the basin A, provided with the extension B on its under side, and extended into a high channeled back, C, above, in combination with mechanism for detachably securing it in position, substantially as described.

3. The urinal comprising a basin, A, provided with the downward extension B, having its lower end adapted to enter an opening in the floor, and a high channeled back provided at its top with a socket, n, in combination with the casing H, having means for securing it to the wall, bolt I, and helical spring K, substantially as described.

4. In a urinal, the basin A, having a high channeled back, C, and downward extension B, provided with the internal shoulder, t, in combination with the cover F, constructed and arranged to operate substantially as described.

ALBERT B. PULLMAN.

In presence of—

ADELBERT HAMILTON,
WM. H. DYRENFORTH.
